UNITED STATES PATENT OFFICE.

MATTHEW T. CHAPMAN, OF AURORA, ILLINOIS.

WELL-SINKING APPARATUS.

No. 833,201.

Specification of Letters Patent.

Patented Oct. 16, 1906.

Original application filed September 25, 1899, Serial No. 731,507. Divided and this application filed December 16, 1903. Serial No. 185,324.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawings.

10 My invention relates to apparatus for sinking wells, and has for its object to provide various improvements by which the sinking of wells may be more expeditiously and satisfactorily accomplished than heretofore. I accomplish this object as herein-after described and as illustrated in the drawings.

What I regard as new is set forth in the claims.

20 In the accompanying drawings, Figure 1 is a side elevation, partly in section, illustrating the devices for supporting the air-pipe and well-tube and apparatus for supplying air and water to the well. Fig. 2 is a section on line 2 2 of Fig. 1. Fig. 3 is a bottom view of a split-sleeve stuffing-box of the well-tube. Fig. 4 is a detail showing a modified arrangement of the air-tube. Fig. 5 is a section on line 5 5 of Fig. 6, showing the clamp for gripping the well-casing. Fig. 6 is a side elevation of the same, showing also the turn-table, some parts being broken away. Fig. 7 is a view illustrating the arrangement of the well in side elevation, some parts being broken away. Fig. 8 is a side elevation of part of the air-pipe, showing the ejector. Fig. 9 is a sectional view of the same. Fig. 10 is a plan view of the parts shown in Fig. 8. Fig. 11 is a plan view of the drill. Fig. 12 is a 40 side elevation illustrating the lower end of the well-casing and the well-sinking apparatus. Fig. 13 is a vertical section illustrating the grooves in the perforated section of the well-casing; and Fig. 14 is a view, partly in section, showing the several parts of my improved apparatus assembled in one figure.

The apparatus illustrated and described in my present application is an improvement upon and in some respects embodies some 50 of the parts of various prior patents issued to me, as follows: No. 382,689, dated May 15, 1888; No. 409,272, dated August 20, 1899; Nos. 443,069, 443,070, 443,071, and 443,072, dated December 16, 1890, and No. 541,835, 55 dated July 2, 1895, to which reference is

made for a full description of the fundamental operation of well-sinking.

For present purposes it is sufficient to say that a tube which forms the well-casing is suspended by suitable apparatus from a derrick placed over the site of the proposed well, said casing having at its lower end a drill adapted to bore through the earth. Suitable guiding devices are provided by which the casing is guided and also apparatus for 65 rotating the casing and drill to cause the drill to bore into the earth. Such rotating devices are so arranged as to permit vertical movement of the casing, so that as the drill penetrates the earth it may descend and the 70 weight of the casing may rest upon the drill to force it down. I prefer to use rotating mechanism which will permit "jumping" of the drill, which consists in raising the casing and then permitting it to drop, thereby causing the drill-point to enter the rock, forming a cut or notch, so that when it is further rotated it engages the rock and drills more rapidly. This is especially necessary where the 75 rock is so hard that the weight of the drill and casing is not sufficient to cause the drill to cut deeply into the rock. In such cases the rotation of the drill operates simply to cut a smooth surface on which the drill rests, and drilling by the rotation of the drill alone 80 would therefore be very slow work. After the well has been bored to a depth almost equal to that of the casing a second length of pipe is screwed upon the upper end of the 85 first, additional sections being added from time to time as the casing descends into the earth.

Referring now to the drawings, 20 indicates the well-casing and 21 a boring-tube which will be termed the "well-tube." The 95 casing 20 is of considerably greater diameter than the well-tube 21 and serves as the casing for the well. In Fig. 1 the well-casing 20 is illustrated as being carried at the lower end of the well-tube 21, said parts being connected by a coupling-head 22, screwed into a sleeve 23, carried at the upper end of the casing. The head 22 may be removed from the casing 20 and another section of casing attached in place of it by the use of suitable 100 tools. After the casing 20 has been sunk to a greater or less depth the drill 24 (see Fig. 14) is usually attached to the lower end of the well-tube instead of to the casing. The 105 well-tube 21 is suspended from a suitably- 110

disposed derrick by a yoke 25, which carries a horizontal plate 26, upon which rests a disk 27, fixedly secured to the well-tube 21, as shown in Fig. 1. Ball-bearings 28 are provided between the disk 27 and the plate 26, as shown in Fig. 1. By this construction the well-tube 21 may rotate freely in the yoke 25. The upper end of the well-tube 21 communicates with a chamber 29, formed in a head 30, supported in the yoke 25, passages 31 being provided between the chamber 29 and the inside of the well-tube 21, as shown in Fig. 1. For preventing leakage the upper end of the well-tube 21 is fitted in a sleeve 32, depending from the head 30, and is provided with a collar 33 and a split stuffing-box 34, the stuffing-box surrounding the well-tube and fitting into the sleeve 32, as shown in Fig. 1. Suitable packing is interposed between the upper end of the stuffing-box and the collar 33, said packing being compressed by bolts 35, which hold the stuffing-box sections in the sleeve 32, as shown. The head 30 is preferably provided with four outlets 36, but a greater or less number may be used. Each of the outlets 36 is provided with a pipe 37, which extends horizontally, the pipe 37 being provided in turn with an upwardly-extending pipe 38, as shown in Fig. 1. The object of the pipe 37 is to form an outlet or inlet for water, the pipe 38 being for the escape of air when the well-tube is used to discharge water from the well under air-pressure.

It will be noted that by the construction above described the well-tube may turn freely within the yoke 25 and head 30 and that the rotation of the well-tube does not affect its connection with the head 30 or the pipe 37.

In Fig. 7 I have shown the well-tube 21 extending down to the bottom of the well and provided with a drill 24. The drill carries a suitable cutting-point 39 at its lower edge and is provided with passages 40, which communicate with the interior of the upper part of the drill, which is hollow and communicates with the interior of the well-tube 21. The drill is usually of about the same diameter as the well-tube, as shown in Fig. 7. Where it is desired to cut the well of a greater diameter than the well-tube, a laterally-arranged cutter 41 is provided, which is secured to an arm 42, which projects laterally from the drill, as shown in Figs. 7 and 11. The cutting-plate 41 is polygonal in form, having a plurality of cutting edges, and is secured to the arm 42 by a bolt 43, so that it is adjustable. By this means when one edge of the cutting-plate becomes dull it may be adjusted to present a fresh sharp edge, thus avoiding the necessity of taking off the drill and sharpening it. In Fig. 12 I have shown a drill 24 without the lateral cutting-plate of a slightly-different shape 55 from that shown in Fig. 7.

44 indicates an air-pipe which is arranged within the well-tube 21 and extends down to near the bottom of the well. The upper end of the pipe 44 extends a short distance above the head 30, passing through a stuffing-box 45 in said head, as shown in Fig. 1, and terminating in a head 46, adapted to be supported from the derrick. The head 46 is provided with an air-chamber 47, with which communicates an air-pipe 48, extending laterally and communicating with an air-compressor 49, as shown in Fig. 1.

49 indicates a collar upon the upper end of the air-pipe 44, which collar rests upon a shoulder 50, formed in the head 46, as shown in Fig. 1.

51 indicates a stuffing-box around the pipe 44 below the shoulder 50 to prevent leakage.

Near its lower end the air-pipe 44 is provided with a nozzle or ejector 52, as shown in Figs. 7, 8, and 9. Said nozzle is provided with an upwardly-inclined annular outlet 53, arranged to discharge the air in an upward direction, and with radially-extending lugs 54, which serve to center the air-pipe. Said nozzle also has a downwardly-extending pipe 55, which extends a short distance below the nozzle 52, as shown in Fig. 7.

As already described, the well-casing 20 extends down to near the bottom of the well, forming a casing therefor. Said casing, however, is not imperforate throughout, as in order to permit water to enter the casing it is provided with one or more perforated sections, such perforated sections being placed in the water-bearing stratum or strata.

In Fig. 12 I have illustrated the bottom of a well where a vein of water of the desired volume is found, so that the well is to be sunk no deeper. The casing 20 is therefore provided with a screen-section 56 at its lower end, which serves to strain the water before it enters the well-casing. Frequently, however, a number of water-bearing strata are encountered which supply only a small amount of water, not sufficient to supply the desired volume, and consequently it is necessary to continue boring. In order to utilize the water from the small veins in boring the well, and thereby avoid the necessity of deriving water for boring purposes from an external source of supply, I provide means whereby the water from such small veins is permitted to flow into the well-casing and then down to the bottom of the well where the drilling is being done. For this purpose the well-casing 20 is provided with an intermediate perforated section 57 of substantially the same diameter as the rest of the casing and provided with a screen 58, covering the perforations and preventing coarse material from entering the casing. In order to facilitate the flow of water into the casing, the outer surface of the perforated section 57 is provided with annular channels 59 and a

series of perforations 60, said perforations being arranged with reference to the channels so that water flowing along one of said channels will sooner or later encounter one 5 of said perforations and pass into the casing. The channels may be formed by cutting screw-threads on the pipe.

In Fig. 7 the water-bearing stratum is illustrated at 61.

10 The operation of the apparatus as thus far described is as follows: The well-casing and well-tube, the latter having within it the air-pipe 44, are suspended from the derrick, the well-casing carrying the drill-point. The 15 drilling operation is then commenced by rotating the casing and the well-tube, water being supplied to the drill-point at first through the pipe 37 and the well-tube. When a water-bearing stratum is penetrated, a per- 20 forated casing-section 57 is placed in the well, so that instead of using an external water-supply the well supplies its own water for drilling purposes. The water entering the casing through the perforated section de- 25 scends to the bottom of the well, then rises through the perforations 40 in the drill to the well-tube 21, carrying with it the debris contained in the well. The water is then ejected by air-pressure, the air being supplied to the 30 well-tube through the pipe 44 and nozzle 52. The outflowing water is discharged through the pipe 37 and may be conducted to any suitable point, such as a reservoir, where after being allowed to settle it may be used 35 again, if necessary. The air contained in the discharge-water may be discharged through the pipe 38.

The operation of supplying water to the well or discharging it therefrom may be conducted coincidentally with the operation of drilling, owing to the swivel-supports for the air-pipe and well-tube.

40 The well-tube 21 or other drilling means may be rotated and otherwise operated for boring the well by means of any suitable mechanism, but I prefer to employ the mechanism illustrated in Figs. 5 and 6 and described in detail in my Patent No. 775,417, dated November 22, 1904, of which this application is a division. It will suffice for the purposes of this application to say that said mechanism consists of a turn-table 62, suitably mounted on a base-plate 64, so as to freely rotate thereon. Said turn-table is 45 driven by any suitable driving mechanism, such as a pinion 65, driven from a shaft 66 and engaging an annular rack 67 on the under side of the turn-table. The turn-table has a central passage through which the well- 50 tube passes and at opposite sides are arranged the members 70 of a clamp-frame having suitable gripping devices in the form of disks 80, which engage the well-tube, so as to cause it to rotate with the turn-table, but 55 permit endwise movement of the well-tube

independently of the turn-table. The members of the clamp-frame are drawn together, so as to cause the disks 80 to grip the well-tube by bolts 77, as shown in Fig. 5. The clamp-frame moves vertically independently 70 of the turn-table on rods 71 72, which are secured in an upright position on the turn-table at opposite sides thereof. By this construction the clamp-frame may rise and fall with the well-tube, but meanwhile is caused to rotate with the turn-table. This construction is fully illustrated and described in my said Patent No. 775,417, and therefore will not be described further in detail herein.

75 In cases where it is not necessary to secure 80 the advantages derived by using the swivel connection for the air-pipe an ordinary elbow, joint may be used, as illustrated in Fig. 4.

In addition to the advantages already pointed out my improved apparatus possesses the further advantage of providing 85 means whereby the various veins of the well are not clogged or closed in the operation of boring, as when boring operations are extended below a water-vein and a screened 90 casing-section placed opposite such vein the muddy water from the bottom of the well does not pass upward through the strainer-section, as owing to the arrangement of the air-pipe and well-tube the water ejected by 95 the compressed air passes up through the well-tube and is discharged without coming in contact with the screen at all. In this way the strainer remains clear, so that the flow of water from intermediate veins into 100 the well is not impeded.

A further advantage is that in boring the well intermediate water-bearing strata are not closed, but, on the contrary, are opened up so as to furnish a free flow of the water, as 105 by the jar occasioned by the operation of the boring machinery the small particles of granular matter from the water-bearing stratum pass freely through the strainer-section, while the larger particles are retained outside of the casing. In this way the finer matter, which would operate to clog or close the vein, is got rid of, leaving the vein free to flow to its fullest capacity.

110 The mechanism for rotating the well-tube, 115 by which the well-tube may be "jumped" and rotated at the same time, is not herein claimed, as it forms the subject-matter of my Patent No. 775,417, hereinbefore referred to.

I have described my improvements in detail; but it will be understood that various modifications may be made, as my invention is not restricted to the specific construction described, except in so far as it is particularly claimed.

That which I claim as my invention, and desire to secure by Letters Patent, is—

120 1. In a well-sinking apparatus, the combination of a swiveled head having an air- 130

pipe connected therewith and extending down into the well, a swiveled well-tube through which said air-pipe extends, said air-pipe opening into the well-tube below the level of the water, whereby the water and debris may be discharged from the well, means for rotating said well-tube, and a drill at the lower end of the well-tube, said drill being hollow and having openings for the admission of water to said well-tube, substantially as described.

2. In a well-sinking apparatus, the combination of supporting devices, outer and inner swiveled tubes connected with said supporting devices, respectively, one of said tubes being an air-pipe and the other a well-tube, boring mechanism connected with the well-tube, means for rotating said well-tube, said air-pipe opening into the well-tube below the water-level, and means for supplying compressed air to said air-pipe.

3. A well-sinking apparatus, having two separate openings, one opening having a pipe connected therewith for conducting compressed air into the well, and a second opening having a pipe connected therewith for conducting the water and debris out of the well, the air-pipe being arranged to discharge below the water-level in the well, the other pipe being revolutely supported, substantially as described.

4. In a well-sinking apparatus, the com-

bination of a well-tube, a yoke supporting said well-tube, said yoke carrying a base, antifriction-balls carried on said base and supporting the weight of said well-tube, and an air-supplying pipe for conducting air down inside of said well-tube and discharging thereinto below the level of the water therein for carrying out the borings and debris from the well as it is being sunk, substantially as described.

5. In a well-sinking apparatus, the combination of a swiveled head, an air-pipe connected therewith and extending down into the well, a swiveled well-tube into which said air-pipe extends, said air-pipe opening into said well-tube below the level of the water therein, and means for rotating said well-tube, substantially as described.

6. In a well-sinking apparatus, the combination of a well-tube, means for rotating said well-tube, a swiveled head connected with the upper end of said well-tube, a bearing-plate secured to said well-tube, antifriction-bearings for said plate, an air-tube extending into said well-tube, and a swiveled support for said air-tube, substantially as described.

MATTHEW T. CHAPMAN.
